UNITED STATES PATENT OFFICE

JACOB SODERBERG, OF PITTSBURGH, PENNSYLVANIA, ASSIGNOR TO PITTSBURGH PLATE
GLASS COMPANY, A CORPORATION OF PENNSYLVANIA

PROCESS AND APPARATUS FOR SUPPLYING SAND TO GRADING APPARATUS

Application filed July 8, 1927. Serial No. 204,229.

The invention relates to a process and apparatus for supplying sand to grading apparatus, and is designed for use primarily in connection with glass grinding apparatus, requiring a continuous supply of sand for use as an abrasive. The invention has for its primary objects the provision of an improved apparatus; which can be operated economically to supply large quantities of sand; which is reliable and requires little attention on the part of the operators in charge of the grinding machine; in which provision is made to avoid any clogging and consequent stoppage of the feed of the abrasive; in which the degree of opening of the control valve is indicated at a point remote therefrom, and in which the valve may be controlled from such point; in which the feed of sand past the control valve is constant and uniform; and which has a reliable regulating means for the water level in the storage tank. One embodiment of the invention is shown in the accompanying drawings, wherein:

Figure 1 is a plan view diagrammatic in part of the apparatus with the grinding mechanism omitted. Fig. 2 is a section on the line II—II of Fig. 1 with the grinding mechanism shown. Fig. 3 is a section on the line III—III of Fig. 1, also showing the grinding mechanism. Fig. 4 is a vertical section on an enlarged scale through the outlet from the storage tank. Fig. 5 is a front elevation, partially in section of the controlling apparatus for the valve of Fig. 4. Fig. 6 is an enlarged section through the valve 57, such valve being shown in neutral position. Fig. 7 is a detail section showing a modification. And Fig. 8 is an enlarged detail section at the top of the storage tank showing the means for maintaining a constant level in such tank.

The particular grinding mechanism with which the apparatus is used is of the straight away type involving the use of the grinding machines 1, 2, 3, etc., arranged in two series (Figs. 2 and 3) along the tracks 4 and 5.

The grinding tables 6, 6, 6, etc., which carry the glass are mounted upon these tracks and move slowly beneath these grinding machines. During this movement, abrasive is

supplied to the machines from the grading tank 7, this being accomplished by the use of suitable conduits, not shown. The grading tank is supplied with a mixture of sand and water from the sump 8 by means of one of the duplicate motor driven pumps 9, which withdraws the mixture of sand and water from the sump and carries it up through the pipe 10. Extending longitudinally beneath the tracks 4 and 5 are the troughs 11, 11, which receive the used abrasive and water from the grinding operation and conduct it back to the sump 8. The foregoing is all old and well-known in the art and the present invention has to do with the apparatus and process for supplying new abrasive to the sump 8. This supply of new abrasive is necessary to take the place of the abrasive which is worn out and lost during the grinding operation.

The source of supply of the sand in the present instance is the stream 12 alongside of which is located the concrete bin 13, having a hopper bottom 14, at one end of which is located the pump 15 driven by the motor 16 and serving to withdraw a mixture of sand and water from the bin through the intake pipe 17 of the pump. Sand is supplied to the bin 14 from the barge 18 by any suitable means, not shown, such as a crane which operates a suitable clam shell digging bucket. The bin may also be supplied from the bank of sand 19 which has been collected along the shore of the stream. The sand, which is pumped from the bin by the pump 15, is delivered through the pipe 20 to the two storage tanks 21, 21. These storage tanks and the feed apparatus connected therewith are duplicates throughout so that a description of one will be sufficient for both. Leading from the bottom of the tank 21 are four outlet passages 22, 22, 22, 22. As later described, each of these outlets is provided with a suitable valve and controlling means and ultimately discharges to one of the pipes 23, 23, 23 and 23 leading to the trough 11. These discharge passages and the controlling means are the same in each case, so that a description of one will be sufficient. The four pipes are used in order to give the necessary capacity to meet all conditions, but it will be under-

stood that a single passage might be employed, and ordinarily only one of the passages is employed, the capacity of one of such passages having been found sufficient to meet most requirements. A description of one of the pipes and its control mechanism will, therefore, be sufficient for all.

The construction of one of the outlets and its controlling means will be best seen by reference to Fig. 4. Secured to the casting 24 at the bottom of the tank is a valve casing 25 in which is mounted the plug valve 26. This valve is ordinarily full open, and is only closed when it is desired to entirely shut down the outlet through the passage. Bolted to the bottom of the casing 25 is a casting 27, which has an opening through one side closed by the cover plate 28 held in position by a loop 29 extending around the casting and carrying the screw 30 for forcing the cover tightly into position. This serves as a clean out means in case the outlet should become clogged, as by a pebble or other obstruction. Below the casting 27 is a rubber tube 31 discharging into the casing 32, to which the pipe 23 is connected. Surrounding the tube and clamping its upper end against the flange of the casting 27 is the casing 33, which carries the controlling means for throttling the tube. This controlling means comprises a clamp member 34 extending around the tube and a movable plate 35, which is adapted to be moved inward to collapse the tube by means of the screw 36. This screw 36 is threaded through the boss 37 on the member 34 and is swiveled to the left hand end of the casing 33 by means of the nut 38. By turning the screw, the plate 35 may be moved inward and so regulate the volume of water and sand passing through the tube 31. In order to start the flow of sand and water from the bottom of the tank 21 after sand has been settled therein, the water supply pipe 39 is provided, having the branches 40, 40, etc., leading into the lower end of the tank and the branches 41, 41, etc. leading into the casings 25. Suitable valves permit the opening and closing of the pipes as conditions may require. A spray pipe 42 is also provided for each of the casings 32 for washing the abrasive along the pipe 23, such pipe being supplied from the pipe 43.

The tube 31 must be regulated in accordance with the amount of new abrasive required in the system and this is determined by the grades in the tank or cone 7. These grades are withdrawn and tested from time to time as the grinding progresses and, if these determinations indicate that there is not enough of certain grades of abrasive in the system, the tubes 31 are opened up slightly to give a greater flow and thus supply the deficiency. On the other hand, if the determinations show that there is too great an amount of certain grades in the system, the tube 31 is collapsed to reduce the amount of

new abrasive fed into the system. As a matter of convenience, it is desirable that the opening and closing of the tubes 31 shall be accomplished from the vicinity of the grading cone 7 and to this end the apparatus shown in Fig. 5 is provided. The end of the screw shaft 36, which controls the position of the plate 35 carries a spur wheel 44 and this spur wheel is adapted to be rotated back and forth by means of the pawls 45 and 46 which are hydraulically controlled by the actuation of the valve 47 which is located adjacent the bottom of the cone 7. The pawls 45 and 46 are carried by the connecting rods 48 and 49 mounted upon the hollow plungers 50 and 51. The cylinders 52 and 53 in which the plungers are mounted have their upper ends connected to the pipe 54 leading to the water supply pipe 43, so that normally the plungers are both held in bottom position. Pressure to move the plungers up is supplied through the pipes 55, 56 leading to the valve casing 57, which carries the valve 47. Leading from this valve casing is an exhaust pipe 58, with which the pipes 55 and 56 may be connected, depending upon the position of the valve 47. Pressure is supplied to the pipes 55 and 56, depending upon the position of the valve 47 from the pipe 59, which is in turn connected to the supply pipe 39. When the handle 60 of the valve 47 is moved to the position shown, pressure is supplied beneath the plunger 50, while the liquid beneath the plunger 51 is exhausted through the pipes 56 and 58. This gives the screw shaft 36 a movement in one direction. If it is desired to give it another step of movement in the same direction, the handle 60 is brought to vertical position, thus bringing the valve to the position shown in Fig. 6, at which time, both of the pipes 55 and 56 are brought into communication with the exhaust pipe 58, so that the pressure from the pipe 54 on the upper sides of the plungers 50 and 51 causes them to move to bottom position. If now the handle 60 is again moved to the position shown in Fig. 5, the spur wheel 44 is given another movement of rotation. When it is desired to reverse the direction of rotation of the wheel 44, the handle 60 is swung to vertical position and then moved still farther to the left. The plunger 50 is thus moved down and the plunger 51 moves up, giving the wheel 44 a movement of rotation in a clockwise direction. This may be repeated by swinging the handle 60 back and forth from its left hand position to its central position, until the desired degree of adjustment is secured. In order that the pawl which is not in service shall be out of engagement with the spur wheel 44, the rollers 61, 62 are provided, so positioned, as indicated in Fig. 5, that when the connecting rod is in lowered position, the 130

pawl will be cammed outward, so that it is free from the wheel 44.

The device shown in the upper portion of Fig. 5 is an indicator which is designed to show the operator the degree of opening of the tube 31. This indicator comprises a spur wheel 63 having a pointer 64 working over the scale 65. This device is calibrated so that the position of the pointer indicates the degree of opening of the tube 31. The wheel 63 is operated by the pawls 66 and 67 connected to the links 68 and 69, such links being connected to arms projecting laterally from the end of the valve 47. The back and forth movement of the handle 60 from the center position to side position rotates the wheel 63 and this direction of rotation depends upon the direction in which the handle is swung from the center position. The pointer 64 can, therefore, be made to assume a position corresponding to the degree of opening of the tube 31. The spur wheels 44 and 63 are each provided with indexing means in the form of the spring pressed members 70 and 71.

In order to maintain the level of the liquid in the storage tank 21 constant, the controlling device shown in Fig. 8 is used. This consists of a ball float 72 arranged to operate a valve in the valve casing 73. This controls the supply of water through the pipe 74 leading from a water supply main. When the level in the tank 21 drops below a certain point, the valve in the casing 73 is opened, admitting water until it reaches the level shown, at which time the valve is closed by the float. The float is located inside a cylindrical casing 75 and the pipe 74 discharges into this casing. This is a desirable arrangement as the inflowing water from the pipe 74 constantly cleans out the casing and washes away any sand which might otherwise collect around the float. The casing also prevents sand from working upward beneath the float and preventing its operation. The storage tank 21 will hold enough sand to supply the necessary abrasive for a long period and is, therefore, only filled at intervals. After it is once filled and while it is being emptied, it is desirable that the water pressure in the tank should remain constant so that the feed from the bottom of the tank will be constant. The means for maintaining a constant level of water in the tank performs this function so that the feed is more certain and uniform under these conditions of constant head pressure.

In order to remove gravel and other foreign matter not suitable for grading, the pipe 20 leading from the bin 14 is made to discharge through the rotary screens 76 and 77, such screens being driven through suitable gearing from one of the duplicate motors 78 and 79. A similar rotary screen 80 receives the flow of water and abrasive from

the drain troughs 11, such screens being rotated by means of suitable gearing from the motors 80' and 81. The overflow water from the storage tanks 21, 21 is conducted back to the bin 14 by means of the pipes 84 and 85.

Fig. 7 illustrates a modification of the arrangement at the lower end of the tank 21, the flexible tube 31^a in this case discharging into a trough 82, which takes the place of the pipe 23 of the Fig. 4 construction. The pipe 42^a supplies the necessary water for washing the sand along the trough and into the trough 11. The trough 82 has a removable cover 83. This construction has the advantage that it permits the attendant to observe the actual condition of the mixture which is being discharged from the storage tank and permits him to know definitely that there has been no stoppage in the outlet. However, the construction of Fig. 4, in which the discharge is through the pipe 23, has a compensating advantage over that of Fig. 7 in that the flow through such pipe 23 may be stopped and started by manipulating the valve 84^a controlling the water supply to the pipe 42. When this valve is closed, the sand quickly fills up the casing 32 and shuts off the supply of sand, which can be started again by opening the valve 84^a. This valve is located adjacent the control valve 47 (Fig. 2), so that the feed of sand from the storage tank 21 can be stopped and started from this point without changing the position of adjustment of the clamping means 34, 35 for the rubber tube 31.

What I claim is:

1. In combination in apparatus for supplying sand to a grading tank, a storage tank having a hopper bottom, means for supplying water with sand in suspension therein to the tank, means for supplying an additional flow of water to the tank, means regulated by the level of the water in the tank for governing such flow, an outlet from said bottom provided with flow regulating means, a sump below the storage tank to which the discharge from said outlet is conducted, and means for continuously supplying the mixture of sand and water in the sump to the grading tank.

2. In combination in apparatus for supplying sand to a grading tank, a storage tank having a hopper bottom, means for supplying water with sand in suspension therein to the tank, an outlet from said bottom provided with flow regulating means, a sump to which the discharge from said outlet is conducted, means for continuously supplying the mixture of sand and water in the sump to the grading tank, power means controlled from a point adjacent the grading tank for operating said flow regulating means, and means indicating the degree of opening of the flow regulating means also located adjacent the grading tank and op-

erated by the means which controls the power means.

3. In combination in apparatus for supplying sand to a grading system, a storage tank having an outlet at its lower end, means for supplying a mixture of sand and water to the tank, a casing at the upper end of the tank extending downwardly into the water in the tank and open at its lower end, a conduit for supplying water into said casing, a valve in the conduit, and a float in the casing for operating said valve.

4. In combination in apparatus for supplying sand to a grading tank, a storage tank having a hopper bottom, means for supplying a mixture of sand and water to the tank at intervals, a sump below the storage tank, an outlet from said bottom provided with a regulating valve, means for conducting the mixture from said outlet to the sump, means for supplying the mixture in the sump to the grading tank, a supplemental water supply for said storage tank, and automatic means regulating said supply and adapted to maintain the level of the water in the storage tank constant.

In testimony whereof, I have hereunto subscribed my name this twenty-eighth day of June, 1927.

JACOB SODERBERG.
